Primary Examiner — Patricia A Palasik*(74) Attorney, Agent, or Firm* — Knobbe Martens Olson & Bear LLP(57) **CLAIM**

The ornamental design for a printer nozzle, as shown and described.

DESCRIPTION

FIG. 1 is a top-side isometric view of a first embodiment of the design for a printer nozzle;

FIG. 2 is a bottom-side isometric view thereof;

FIG. 3 is a first side view thereof;

FIG. 4 is a second side view thereof;

FIG. 5 is a third side view thereof;

FIG. 6 is a fourth side view thereof;

FIG. 7 is a top view thereof; and,

FIG. 8 is a bottom view thereof.
